DESIGN FOR AN INKWELL

Loid Crandall, John W. Davis, and Lorentz J. Lindquist, Los Angeles, Calif., assignors to Harry A. Morgan, Los Angeles, Calif.

Application January 10, 1936, Serial No. 60,507

Term of patent 3½ years

To all whom it may concern:

Be it known that we, Loid Crandall, John W. Davis, and Lorentz J. Lindquist, citizens of the United States, residing at Los Angeles, in the county of Los Angeles and State of California, have invented a new, original, and ornamental Design for an Inkwell, of which the following is a specification, reference being had to the accompanying drawing, forming part thereof, in which:

Figure 1 is a plan view of an inkwell showing our new design,

Figure 2 is in front elevation,

Figure 3 is a side elevation.

We claim:

The ornamental design for an inkwell, as shown,

LOID CRANDALL.

JOHN W. DAVIS,

LORENTZ J. LINDQUIST.
